UNITED STATES PATENT OFFICE.

SAMUEL K. LEITER, OF CHICAGO, ILLINOIS.

SMOKE AND GAS CONSUMER.

SPECIFICATION forming part of Letters Patent No. 239,517, dated March 29, 1881.

Application filed September 20, 1880. (No model.)

To all whom it may concern:

Be it known that I, SAMUEL K. LEITER, of the city of Chicago, in the county of Cook, of the State of Illinois, have invented a new and useful Improvement in Smoke and Gas Consumers, of which the following is a specification, reference being had to the annexed drawings, forming a part thereof, which will enable others skilled in the art thereto pertaining to make and use the same.

My invention pertains to a device attached to a cooking-stove, range, or other stove or furnace, for the purpose of consuming the smoke and gas, and of perfecting the combustion of the fuel in the fire-box.

In the drawings, Figure 1 is a vertical cross-sectional view of the fire-box and a portion of the upper smoke passage or flue of a cooking-stove, and of my device attached thereto. Fig. 2 is a vertical longitudinal sectional view of the same, and Fig. 3 is a perspective exterior view of my device.

Letters and figures of like name and kind refer to like parts in each of the figures of the drawings.

My said invention consists of a box or combustion-chamber, A, of cast-iron or other suitable metal or other material, of which the rear edge, a, and the two ends a' a' are provided with perforations a², and the upper side, a³, and lower side, a⁴, incline divergently from the edge a to the open front or mouth of the chamber. The lower side, a⁴, is prolonged into a downward-curved lip, a⁵.

This device, when applied to a cooking-stove or range, B, as shown in the drawings, is arranged horizontally in the center of the upper smoke passage or flue, b', in the direct line of draft, between the fire-box b and the flue-pipe

of the stove, (herein not shown,) in such a position that the lip a⁵ laps over and downward upon the back fire-wall, b², of the fire-box, and that the upper side, a³, is against the top plate, b³, of the stove, to which it is in any suitable manner secured.

The device being thus constructed and arranged within the stove, the smoke and gas, being drawn into the combustion-chamber against the hot metal and through the perforations, are superheated and perfectly consumed.

Having thus described the said device, what I claim as new, as my invention, and desire to secure by Letters Patent, is—

1. In combination with a cooking-stove, range, or other stove or furnace, a combustion box or chamber, A, provided with perforations a², or their equivalent, in the rear edge, a, and ends a' a', substantially as described, for the purposes set forth.

2. In combination with a cooking-stove, range, or other stove or furnace, a combustion box or chamber, A, having divergently-inclined sides a³ and a⁴, and perforations a² in the rear edge, a, and ends a' a', substantially as described, for the purposes set forth.

3. In combination with a cooking-stove, range, or other stove or furnace, a combustion box or chamber, A, having perforations a² in the rear edge, a, and ends a' a', and the downward-projecting lip a⁵ of the lower side, a⁴, substantially as described, for the purposes set forth.

In witness whereof I hereunto set my hand this 16th day of September, A. D. 1880.

SAMUEL K. LEITER.

In presence of—

DANIEL STORER,
L. H. HARLAND.
